UNITED STATES PATENT OFFICE.

GEORGE B. THOMAS, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

ELECTRICAL CONNECTER.

Application filed March 11, 1925. Serial No. 14,768.

My invention relates to electrical connectors, and particularly to features of the connector related to its contacts. Among the objects of my invention are (1) to provide a contact which in itself is of improved construction, and (2) to so mount a pair of such contacts in the connector body that they may shift transversely across their respective chambers to accommodate variously spaced jacks, while still maintaining parallelism in all positions.

In the accompanying drawings—

Fig. 1 is a broken plan view of a connector in which my invention is embodied in one form;

Figs. 2 and 3 are more or less diagrammatic partial sections showing the contacts in opposite extreme limits of movement transversely of their chambers to accommodate jacks of different spacings;

Fig. 4 is a partial section through the connector;

Fig. 5 is an exploded view of one of the connector contacts;

Fig. 6 is a broken side elevation of a modified contact construction;

Fig. 7 is a broken plan view thereof; and

Fig. 8 is a perspective view of a detail of the contact.

The connector in the form shown comprises a pair of complementary blocks 15 and 16 of insulating material, recessed on their juxtaposed faces to form a pair of contact housing chambers 17 and 18 spaced

apart by the barrier rib 19. The chambers are open at one end to afford guide channels 20 and 21 through which enter the jacks of an associated attachment plug (not shown). In the form illustrated in Figs. 1

to 5 inclusive the connector 15 embodies a switch mechanism (not shown) operated by a thumb lever 22 and serving to control the connection to one or both of the contacts located in the chambers 17 and 18.

In the channels 23 and 24 which lead to the chambers 17 and 18 are conducting straps 25 and 26 to which the contacts are electrically connected.

Each contact comprises a link 27 pierced at one end 28 to accommodate a securing screw 29 by means of which the contact is

anchored and electrically connected to one or other of the straps 25, 26. Each strap 26 is secured to the block 16 by a molded-in hollow rivet 30 tapped to receive the screw 29. A spacer 31 interposed between the link 27 and the rivet 30 serves to locate the link 27 substantially in the mid-plane of the chamber 18. At its opposite end the link 27 is pierced at 32 to accommodate a rivet 33 by which the attaching ends 34 and 35 of the contact leaves, as well as the ends 36 and 37 of the associated spring forks are secured in swivelling relation to the link 27.

The leaves of each contact are identical and are struck from sheet metal, preferably copper, or other good conductor of electricity, which has little inherent strength or resiliency. The shank of each leaf is longitudinally apertured at 38 to increase its flexibility and the side rails 39 and 40 so formed are offset at the jack-receiving end of the contact to form a flared lip 41. Intermediate the rails 39 and 40 at the lip of each leaf, the connecting integral web 42 is bowed outward to form, with its associated leaf, a longitudinal cylindrical channel for the accommodation of cylindrical jack pins. Thus each contact is adapted to receive jacks of either the pin type which enter the longitudinal channel 43, or of the blade type which is engaged between the opposed side rails 39 and 40 of the contact leaves.

To reinforce the leaves mechanically and cause them to grip an inserted jack of whatever type, each contact comprises a pair of forks 44 and 45 of spring steel, the legs of which straddle the longitudinally bowed areas 42-43 of the leaves and bear upon the respective side rails 39 and 40 adjacent the lip of the contact.

The leaves and spring forks are firmly united to form an integer by the rivet 33 which passes through the registering apertures 46 in the attaching ends 34, 35, 36 and 37 of the several contact parts, as well as through the hole 32 in the link 27. For the better securing of the contact leaves and spring forks, the apertures 46 may be rectangular and the rivet 33 similarly shaped, the hole 32 in the link 27 being of sufficient

diameter to accommodate the square shank of the rivet.

The chambers 17 and 18 in the insulating body of the connector are of sufficient width to accommodate the contacts with considerable lateral clearance. It is thus possible for the contacts to move apart as indicated in Fig. 2 to accommodate themselves to jacks of wide spacing, or alternately to move toward each other to accommodate themselves to jacks of less spacing. As the contacts move transversely in either direction, they maintain their parallelism by reason of the swiveling connection at the rivet 33 with the link 27. It will be realized that precise parallelism is not necessary and that in case one of the jacks is out of parallel with its companion, either of the contacts may assume an angular relation with respect to the other to accommodate itself to this deformed condition of the jack.

In Figs. 6 and 7 I have illustrated a contact which does not embody a link 27—a construction which may be used to advantage in a connector having floating contacts to which the wires are directly connected. In this form the ends 47 of the contact leaves are extended sufficiently to afford appropriate binding terminal plates adapted to receive the binding screw 48 which passes through registering holes therein, and takes into a clamping washer, or the like, 49. The rivet 50 is shouldered at 51 to form a spacer, while the ends 52 of the rivet pass through registering holes, not only in the leaves but also in the spring steel forks 53, and are offset to rigidly unite the parts together. The shape of the contact leaves and spring forks is in every material respect identical with that above described.

In both types of construction, the contact has the merit of presenting a good conductor of electricity to the cooperating jack, while a spring grip upon the latter is secured by the spring forks which carry substantially no current and are consequently not subject to deterioration by heat incident to internal resistance. The temper of the springs is therefore retained for a much longer period than is the case where the spring is called upon to carry current. Moreover the metal of the spring forks may be of a nature capable of receiving a much higher temper. The spring forks apply their pressure to the contact leaves adjacent the lips of the latter—a point at which the effort is exerted most effectively, and secondly the point at which it is most essential that pressure be applied, since the engagement of the contacts with the jacks occurs solely in this region in the case of cylindrical jacks, and principally in the case of jack blades. Moreover it is desirable that pressure be exerted adjacent the contact lips since it is

at this point that the circuit is broken when the plug jacks are withdrawn, and it is of advantage to maintain the electrical connection between the connector contacts and the plug jacks as complete as possible until the jacks are fully withdrawn in order to prevent loose engagement between the parts and consequent heating or arcing during this operation.

It will be realized that various modifications in details of construction and arrangement of parts may be made without departing from what I claim as my invention.

I claim—

1. In an electrical connector, a contact comprising opposed contact leaves, plate springs independent thereof and extending longitudinally of the contact leaves and constantly urging the latter toward each other to grip an inserted jack, and means rigidly uniting said contact leaves and plate springs at a point remote from the jack-receiving end of the contact.

2. In an electrical connector, a contact comprising opposed contact leaves, each longitudinally grooved to afford side rails and an intermediate channel, longitudinally extending plate spring forks straddling the channels of the respective contact leaves and constantly urging the latter toward each other to grip an inserted jack, and means rigidly uniting said contact leaves and plate springs at a point remote from the jack-receiving end of the contact.

3. In an electrical connector, a contact comprising opposed contact leaves, each longitudinally grooved to afford side rails and an intermediate channel, longitudinally extending plate spring forks straddling the channels of the respective contact leaves and bearing against their respective side rails adjacent the jack-receiving ends of said contact leaves, together with means rigidly uniting said contact leaves and plate springs at a point remote from the jack-receiving end of the contact.

4. In an electrical connector, an insulating body, a pair of contacts housed within the body and shaped to afford substantially parallel jack-receiving channels, a fixed conductor housed within the body and a link connecting said conductor to one of said contacts to permit lateral movement of said contact toward and from its companion contact while maintaining parallelism between the jack-receiving channels of said contacts.

5. In an electrical connector, a contact comprising opposed contact leaves, plate springs extending longitudinally of the contact leaves and constantly urging the latter toward each other to grip an inserted jack, and means rigidly uniting said contact leaves and plate springs at a point remote from the jack-receiving end of the contact, in combination with a fixed conductor and a link

pivots connected to the contact and to said fixed conductor.

6. In an electrical conductor, an insulating body recessed to afford a pair of contact chambers, a pair of fixed conductors for leading current to one end of each of said chambers, a transversely floating contact in each chamber, and for each contact a link pivoted thereto and to its related fixed conductor, to establish electrical connection therewith while permitting the contacts to maintain parallelism while floating in their respective chambers.

In testimony whereof I have signed my name to this specification.

GEORGE B. THOMAS.
